UNITED STATES PATENT OFFICE.

EDWARD GIBSON, OF JERSEY CITY, NEW JERSEY.

STEAM-BOILER SETTING.

SPECIFICATION forming part of Letters Patent No. 723,860, dated March 31, 1903.

Application filed April 19, 1902. Serial No. 103,794. (No model.)

To all whom it may concern:

Be it known that I, EDWARD GIBSON, a citizen of the United States, residing in Jersey City, in the county of Hudson, in the State 5 of New Jersey, have invented a certain new and useful Improvement in Steam-Boiler Settings, of which the following is a specification.

It has long been common to complete the combustion of the gaseous products rising 10 from the coal in a steam-boiler furnace by supplying fresh air in small jets thereto and also to supply air for such purpose by the force of steam-jets. Steam properly conditioned is not wet, and it is found to be no injury, but 15 rather an advantage, to have the steam mingled with the air before it is projected into the current of gases. I have devised important improvements in the apparatus for attaining these ends.

20 I provide boxes, which I will term "shells," of cast-iron or equivalent strong material which is a good conductor of heat, and mount such immediately in the rear of what is technically known as the "bridge-wall." I provide 25 such cases with perforations distributed so as to eject jets of air in any required direction, usually upward and also both forward and backward, and I provide passages in the walls of the furnace through which mingled 30 air and steam are brought upward from the ash-pit and delivered into such boxes, one such air-passage being provided on each side. I blow the air and steam into the ash-pit by the force of powerful steam-jets delivered 35 from pipes subjected to the full pressure of the steam in the boiler. I superheat the steam, abstracting heat therefor from the gases after they have passed the bridge-wall and have imparted so much of their heat to 40 the boiler that they are considerably lowered in temperature, but are still hot enough to serve usefully in not only thoroughly drying but superheating the steam. There is a refrigerating effect produced on the gases by the 45 presence of the superheating-pipes. The fact that they are located in rear of the bridge-wall insures that such has no influence on the heat of the furnace, which is the main steam-generating agency; but it is important 50 to preserve the heat of the gases for a considerable distance after they have passed the wall—in fact, till they part company with

the boiler. I provide for defending the gases against being too much cooled by the presence of the superheating-pipes along the side 55 walls. There is also a liability under some conditions for the pipes to become too highly heated. This is most likely to occur when the fire is very hot and the steam is for some reason shut off, so that it does not circulate 60 through the superheating-coils. I have devised a series of shields and means for holding them in place, which serve two useful purposes—that of reducing the refrigerating effect of the heating-pipes on the gases and de- 65 fending the superheating-pipes from becoming too highly heated under any conditions. The construction of these shields and their adjuncts allows the hot gases to circulate to a limited extent around the superheating-pipes 70 and to make the extent easily contractible.

The following is a description of what I consider the best means of carrying out the invention.

The accompanying drawings form a part of 75 this specification.

Figure 1 is a longitudinal vertical section on the line 1 1 in Fig. 2. Fig. 2 is a duplicate figure, the left side being a vertical cross-section on the line 2 2 in Fig. 1 and the right 80 half being a section on the line 2^X 2^X in Fig. 1. Fig. 3 is a front view of the boxes which constitute the top of the fire-bridge. Figs. 4 and 5 are on a larger scale. Fig. 4 is a face view 85 of one of the tiles, seen from the interior of the secondary combustion-chamber. Fig. 5 is a vertical section on the line 5 5 in Fig. 4.

Similar letters of reference indicate corresponding parts in all the figures where they appear.

A indicates the boiler; A', the ordinary lugs riveted on the sides to aid in supporting it on the side walls; M M, the walls, and m the flues or short inclined channels in the walls which convey the mixture of steam and air upward 95 from the ash-pit and obliquely backward to pour them into the shells.

C is the grate, and L the lower and main portion of the fire-bridge, and a the secondary combustion-chamber.

It will be understood that all the parts not particularly referred to may be of any ordinary or suitable construction.

E indicates the shells, and e the perfora-

tions therein through which the fresh air mixed with steam and at a high temperature is discharged into the gases to complete the oxidation or burning of any combustible material therein.

B is a small steam-pipe leading from the dome of the boiler. This extends downward to a point inside of the wall M in rear of the bridge-wall, where it forms a series of returns, (indicated by B'). From the lower end of these returns the pipe extends forward, as indicated by B², and brings the steam highly heated to a tapering spiral or snail-formed coil B³, mounted in a suitable aperture in the wall communicating with the ash-pit. This pipe may be made in any number of lengths coupled together and supplied with one or more controlling cocks or valves B⁴.

N is a channel-iron built into the wall M, extending along directly over the returns B', one edge projecting inward and upward, as shown in Figs. 2 and 5.

M' indicates bricks set in the wall projecting therefrom into the secondary combustion-chamber *a* below the lowest of the superheating return-pipes. Another row of bricks (marked M²) are set immediately below M' and projecting farther from the wall, as shown in Fig. 5.

P is one of a series of specially-formed shields made of fire-clay. Each has perforations *p*, and each is provided with a hook P', by which it can be hung upon the projecting edge of the channel-iron N. The depth of these shields is such as to nearly but not quite extend down to the series of bricks M². In other words, the lower edges of the shields rest in the rabbet formed by the bricks M' M². These shields, by the aid of the channel-iron N above and bricks M' M² below, inclose the returns B'. They may be hung on the iron with a little space between them, so that while the tiles shield the superheating-pipes from ever becoming very intensely heated they are certain to be kept at a moderately high temperature and able to properly superheat the steam flowing through them whenever the furnace is operating. The heat in the gases traversing rearward through the main body of the secondary combustion-chamber *a* raises the temperature of the pipes B' by the conduction of the heat through the material of the shields P and also by radiating through the perforations *p* and more or less through the vertical joints, the vertical edges where the several shields form a series applied approximately but not tightly against each other.

When the apparatus is in operation, steam flows from the boiler through the pipe B, returns B', extension B², and snail B³, escaping in fine strong jets from the latter and drawing in fresh air, raising the pressure in the ash-pit. Much of the air and steam goes upward through the grate C and blows the fire in the ordinary manner. Another portion of such air and steam, that with which this

invention deals, rises through the inclined passages *m* on each side and entering the shells E blows out in gentle jets through the perforations *e* in the latter and induces complete combustion of the gases flowing away from the furnace. The volume of hot gaseous products flowing rearward through the secondary combustion-chamber performs its usual function of heating the boiler above and contributing directly to the generation of steam, and in addition heats the return-bends B' through the interposed shields and induces a superheated condition of the steam, which contributes to the heat in the ash-pit and furnace.

The material of the snail B³ and of the perforated cap thereon should be copper. The shells or bridge-wall caps E should be of cast-iron.

Modifications may be made without departing from the principle or sacrificing the advantages of the invention. I have shown the superheating-pipes and the shields on one side—the left side—only. A corresponding set of apparatus may be mounted on the opposite side. I have shown the inclined passages *m* on each side of the furnace, bringing the hot air and steam under gentle pressure upward and pouring them in at each side of the fire-bridge, and such construction allows the shells to be made in two separate castings mounted independently and to have their inner ends closed; but by making the shells all in one or by making two or more and having the passages open across the whole breadth I can make the invention serve usefully with only one passage *m*—that is to say, with only the inclined flue *m* shown on the right-hand side or the left without the other.

Some of the advantages due to certain features of the invention may be separately enumerated as follows: First, by reason of the furnace having a steam-blower B³ and the fact that the secondary combustion-chamber, by which I include all the horizontal passage *a* in rear of the fire-bridge, is of such depth as will allow of contraction laterally, and of the series of return-pipes B', arranged within such passage at one side, with a suitable connection B for receiving steam from the boiler and a suitable extension B² for conveying the steam therefrom to the blower, I am able to temper the effect of the gases and insure a moderately high degree of superheating under all conditions and to attain such end without in any wise cooling the wall M in front of the fire-bridge, so as to diminish the effect of the fire in that important part of its steam-generating work; second, by reason of the furnace having a steam-blower B³ and of the series of return-pipes B', arranged within the secondary combustion-chamber *a* at one side, with a suitable connection B for receiving steam from the boiler and a suitable extension B² for conveying the steam therefrom to the blower, and of the employment therewith of the series of perforated

shields P P', of fire-brick, extending nearly continuously between such returns and the current of variably hot gases traversing the remainder of the connection, I am able to still 5 more evenly temper the effect of the gases and insure a moderately high degree of superheating under all conditions and to attain such end without in any wise cooling the wall M in front of the fire-bridge, so as to 10 diminish the effect of the fire in that important part of its steam - generating work; third, by reason of the further fact that the channel-iron N is permanently set in the wall M in rear of the fire-bridge, with its flange 15 presented upward, and of the manufacture of the shields P, each separately provided with a hook P', formed integral therewith, I am able to easily and rapidly apply and remove the shields and to change the width and the 20 distribution of the spaces between them to attain the best conditions with various fuels; fourth, by reason of the further fact that the passages m are recessed into the side walls M in front of the fire-bridge and inclined, as 25 shown, and that the shells E e are of metal, which conducts the heat rapidly, and that they open laterally, so as to freely receive and distribute along its whole breadth the air mixture to be discharged through such passages, 30 I am able to heat the jets of air and steam and to promote the burning of the combustible matter in the gases without obstructing or in any way interfering with the usual flow of the gases from the furnace to and over the 35 fire-bridge.

I claim as my invention—

1. In a steam-boiler furnace, the combination of a bridge-wall dividing the furnace into a primary combustion-chamber and a secondary combustion-chamber, a series of returns B' arranged in the secondary combustion-chamber and constituting a superheater and connections between the boiler, the returns and the blower, whereby steam super-

heated by the gases after they have passed 45 the bridge-wall is supplied to the blower, substantially as specified.

2. In a steam-boiler furnace, the combination of a bridge-wall dividing the furnace into a primary combustion - chamber and a secondary combustion-chamber, with shielding devices P of fire-brick material arranged at the side, a series of returns B' arranged in the secondary combustion-chamber between such shields and the side wall, and constituting 55 a superheater and connections between the boiler, the returns and the blower, whereby steam superheated by the gases after they have passed the bridge-wall is supplied to the blower, substantially as described. 60

3. In a steam-boiler furnace having a secondary combustion-chamber a with a boiler A and steam-blower B³, in combination with the returns B' in the connection between them, arranged as shown with the iron N, permanently set in the wall M in rear of the fire-bridge, and the series of perforated shields P having hooks P' made integral therewith, adapted to match on such iron, all arranged to serve substantially as herein specified. 65

4. In a steam-boiler furnace, the walls M having passages m recessed therein extending forward and rearward of the fire-bridge, and the metal shells E extending along the top of the fire-bridge and connecting with 75 such passages at the sides, such shells being provided with apertures e adapted to discharge into the gaseous products of combustion, combined and arranged to serve substantially as herein specified. 80

In testimony that I claim the invention above set forth I affix my signature in presence of two witnesses.

EDWARD GIBSON.
